N. S. Wedder & Ezra Ripley of Troy, New York
Assignors to

Sweetland and Little of Lanescent, New York
Letters Patent No. 827, Dated August 26th 1836.

The schedule referred to in these Letters Patent and making part of the same.

To all whom it may concern:

Be it known that we, N. S. Wedder & Ezra Ripley, each of the City of Troy, in the County of Rensselaer, and State of New York, have jointly invented or produced a new and original design for the end and side plates of a "Fig Plate Stove", which we call the "Forest Rose"; and we do hereby declare that the following is a full and exact description of the same, reference being had to the annexed drawings, making a part of this specification, in which Fig. 1, is an elevation of the end plate, and Fig. 2, an elevation of the side plate.

The design of the end plate is composed of the curved bead-moulding E and a, arranged upon surface, and enclosing the tablet D, for the name of the manufacturer - and also the raised and swelling oval panel with truncated ends; which panel has the check-work ground surface C, C, - composed of small square pyramids, - and supports, in the center, the opening rose, A, upon a plain surface, surrounded by raised

leaf-like mouldings M, M' ; which latter terminate at the top, in the side scrolls B, B' ; and the central ornament J , and have the double supporting scrolls K, K' , at the bottom of the panel: - all the parts being arranged together and shaped as particularly shown in Fig. 1.

The side plates is of the oblong shape shown in Fig. 2. and its general vertical curvature is indicated by the hincry, Z , Fig. 1. but it is straight horizontally. The ornamental design of this side plate is composed of the check-work surface H , supporting, at the center, the opening rosette F , on a plain circular tablet, surrounded by the compound leaf-like mouldings I, I' , which terminate at the bottom, in the central scrolls Q, Q' , at the top, in the scrolls R, R' having the central compound ornament G , between them; and at the sides, in the upper double scrolls N, N' and N^2, N^3 , and, by the zigzag mouldings O, O' , in the lower scrolls P, P' , - these upper and lower scrolls being connected together by the band-like mouldings S, S' , and the whole surrounded by the plain border T ; all the parts being formed and arranged together as particularly shown in Fig. 2.

What we claim as our invention or production, and desire to secure by letters patent, is the ornamental design of the end and side plates of a six plate stove, the same as herein described and represented in the annexed drawings.
